DESIGN FOR AN AIR DEFLECTOR

Ross M. Clayton, Asbury Park, N. J., assignor to
Air-Col Corporation, a corporation of New
Jersey

Application July 8, 1944, Serial No. 114,437

Term of patent 14 years

(Cl. D62—4)

To all whom it may concern:

Be it known that I, Ross M. Clayton, a citizen
of the United States, residing at Asbury Park,
in the county of Monmouth and State of New
Jersey, have invented a new, original, and ornamental
Design for an Air Deflector, of which the
following is a specification, reference being had
to the accompanying drawing, forming part
thereof.

The figure is a perspective view of an air deflector showing my new design.

I claim:

The ornamental design for an air deflector, as
shown.

ROSS M. CLAYTON.
